ATTORNEY

UNITED STATES PATENT OFFICE.

LOUIS ROSENBERG, OF NEW YORK, N. Y.

CAN.

Application filed May 11, 1925. Serial No. 29,316.

This invention relates to sheet metal cans such as are used as receptacles for ashes and other refuse materials, and also to any other metal receptacle subject to rough handling 5 in connection with heavy service.

One of the objects of the invention is to provide a can having longitudinal re-enforcements on its sides and an annular re-enforcement at its base, in addition to the bands 10 commonly used.

It is a further feature to incorporate with the lateral re-enforcements, resilient bars, acting as shock absorbing elements, adapted to reduce the impact of articles brought into 15 forcible contact with the can, thus materially prolonging its usefulness and also minimizing the noise from such concussion.

Another aim is the provision of an efficient cushion at the base, metal clad, and capable of limited movement whereby the 20 shock of dropping the receptacle upon a rigid surface is transmitted only partially and indirectly to the receptacle body, thus minimizing the effect of the shock.

25 A further object is the provision of an efficient buffer for attachment to the bottoms of receptacles to absorb the shock of heavy impact.

These objects are achieved by the novel 30 construction and combination of parts hereinafter described and graphically delineated in the associated drawing, forming a material part of this disclosure, and in which:—

Figure 1 is a top plan view of a can 35 made in accordance with the invention.

Figure 2 is a side elevational view of the same.

Figure 3 is a bottom plan view thereof, 40 partially in section.

Figure 4 is a fragmentary sectional view taken on line 4—4 of Fig. 5, showing a modified type of re-enforcement and cushion rib.

Figure 5 is a partial longitudinal sectional view taken through one of the cushioning 45 ribs near the top of the can.

Figure 6 is a similar sectional view of the base portion of the can.

Figures 7, 8 and 9 are transverse sectional views showing different forms of the cushion 50 ribs.

Figure 10 is a side view, and Fig. 11 a bottom view of a cylindrical receptacle showing a modified application of my invention.

Figure 12 is a side view, and Fig. 13 is

a bottom view showing a further application of the invention.

Figure 14 is a detail partly in section showing a modified form of the buffer element.

The body of a generally cylindrical sheet metal can is designated by the numeral 10 having a fixed imperforate bottom 11, handles 12 and upper and lower re-enforcing bands, respectively 13 and 14, riveted to the body in the usual manner.

Fixed at uniformly spaced intervals on the periphery of the can body to extend longitudinally, are a plurality of channel shaped ribs 15, the cross section of which is shown in the detail Fig. 7, or 15', as in Fig. 8, or the modified form 15'', as in Fig. 9, all of 50 which answer the same purpose.

Fixed at uniformly spaced intervals on the periphery of the can body to extend longitudinally, are a plurality of channel shaped ribs 15, the cross section of which is shown in the detail Fig. 7, or 15', as in Fig. 8, or the modified form 15'', as in Fig. 9, all of 55 which answer the same purpose.

75 The ends of these several ribs are bevelled, as at 16, flat continuing portions 17 extending under the bands 13 and 14 to be firmly held against the walls of the can.

Tightly held in the channels are bars of 80 elastic, resilient material, as 18, 18' or 18'', of rubber or equivalent substance, the outer portions of these bars extending to such distance that a line drawn from one bar to the next adjacent will be slightly outward beyond the tangential line making contact with the body of the can, as at 19, in Fig. 1.

Thus it will be seen that if the can is 85 brought into forcible contact with a flat surface, shock and noise will be effectually absorbed by the cushion rib elements 15.

In the modification illustrated in Figs. 4 and 5, the walls of the can 10 are indented longitudinally producing recesses 20, having 90 convergingly inclined side walls, between which are set resilient bars 21.

The ends of each indentation taper outwardly from below the bands 13 and 14 to the full diameter of the can, and receive the 95 ends 22 of the bars 21 as best shown in Fig. 5.

A plurality of studs or pins 23 having enlarged heads, are riveted into the wall material at the bottoms of the recesses, to pass 100 through corresponding openings in the bars to retain the same in position.

It will be understood that the side walls of the recesses act effectively as strengthening or re-enforcing corrugations, and that 105 the rubber or like inserts are adapted to act as buffers for the can in the manner previously stated.

The lower band 14, in addition to being riveted, together with the annular flange 11^a of the bottom 11, is enveloped between the upstanding annular walls 24 and 24' of a bulbous loop 25.

Enclosed in the loop 25 is a rubber or like resilient endless ring 26, in which are set at intervals a plurality of semi-circular metal caps 27, adapted to make contact with the combined edges of the elements 10, 11' and 14 which are normally spaced therefrom, as at 28, in Fig. 6.

These several plates are held in intimate relation by rivets 29 passing through enlarged openings 30 in the several plates, permitting a moderate but limited amount of relative movement between the metal clad cushion ring and body of the can.

In the modification illustrated in Figs. 10 and 11 a receptacle 10^a, such as is used commercially for the handling of milk is provided with buffers 25^a, similar in all respects to the bulbous loop 25, shown in Figs. 2 and 6, except that instead of entirely surrounding the bottom of the can they are comparatively short metal sections spaced apart as legs, each enclosing a resilient element 26^a adapted to make contact with the bottom edge of the wall 10^a of the can and held in intimate relation by similar rivets 29 passing through enlarged openings 30 in the wall of the receptacle.

The modifications illustrated in Figs. 12 and 13 show the application of similar buffers to a rectangular receptacle 10^b, right angled buffers 25^b being used at the corners and straight sections or buffers 25 being used on the straight sides.

Instead of using semi-circular caps 27 with which the sides of the receptacle make contact to prevent wearing a groove into the resilient element 26, the studs 27^b may be embedded into the resilient element as best shown in Fig. 14.

Although I have described my improvements with considerable detail and with respect to certain particular forms of my invention, I do not desire to be limited to such details, since many changes and modifications may well be made without departing from the spirit and scope of my invention in its broadest aspect.

Having thus described my invention what I claim as new and desire to secure by Letters Patent, is:—

1. A sheet metal can having a plurality of longitudinal ribs, said ribs being essentially of channel shaped cross section having convergingly inclined side members and bands at the ends of the can confining the ends of said ribs thereto.

2. As an article of manufacture, a buffer for the bottom of metal receptacles, comprising a resilient element, a casing for said element, parts of said casing adapted to be attached to the receptacle to permit contact between the base edge of the receptacle and the resilient member, metallic wear caps between the resilient member and the base edge of the receptacle, and means permitting limited relative movement between said base edge and the resilient member.

Signed at New York, in the county of New York and State of New York, this 28th day of April 1925.

LOUIS ROSENBERG.
